LUG STRAP AND POWER STICK FOR LOOMS

Frank L. Furgal, Dover, N. H.

Application January 9, 1945, Serial No. 572,025

4 Claims. (Cl. 139—152)

1

This invention relates to improvements in power sticks and sweep stick connections and avoids the use of the conventional lug strap, providing for longer wear, ease of adjustment, and other advantages.

Objects of the invention reside in the provision of an adjustable power stick and holder therefor mounted on the picker stick stud shaft and pivoted to a sweepstick connection having rigid parts for longer use, the connection being reversible and useful at either side of the loom without change.

Other objects and advantages of the invention will appear hereinafter.

Reference is to be had to the accompanying drawing, in which

Fig. 1 is a view in the side elevation of a form of the invention;

Fig. 2 is a section on line 2—2 of Fig. 1;

Fig. 3 is a top plan view of Fig. 1; and

Fig. 4 is a detail of a bumper.

In the drawing there is shown a conventional picker stick 10 mounted on the stud shaft 12 in the usual manner. A holder comprising a metal plate 14 having side flanges 16 and a central slot 18 is also mounted on the picker stick stud shaft, and contains and supports between the flanges 16 a power stick 20. The latter is longitudinally adjustable in the holder by means of bolts 22 taking in slot 18.

At its upper end the power stick is provided with a pair of apertures 24 for adjustably receiving a sleeve 26, the latter being longer than the thickness of the power stick and extending out from each side thereof. The sleeve spaces the power stick from a metal plate 28 and from an offset strap 30 to allow for play between these parts. The offset strap and the plate 28 carry a bolt 32 passing through the sleeve to connect the parts.

A second parallel metal plate 34 is secured in spaced relation to the plate 28 by a bolt 36 carrying between the plates a series of octagonal leather washers 38 acting as a bumper for the picker stick, although the invention contemplates the use of bumper plate 40 also. The washers 38 may be rotated to present a plurality of different bumping faces to the picker stick. The bumper plate 40 is provided with recesses 41 receiving plates 28 and 34 to detachably secure the bumper plate. The picker stick is located between the plates as indicated in Figs. 2 and 3,

2

and the plates are adjustably secured to the sweep stick 42 at their ends, and mount leather wear plates 44 at this point. The sweepstick is adjustable relative to the plates 28, 34 by means of a bolt and slot connection 46.

The head 48 of bolt 32 keeps the picker stick generally out of engagement with plate 28, there being a tendency for the picker stick to rub on this plate.

10 It will be clear that by removing the power stick, the holder plate, and plates 28 and 34 as a unit, the plates 28, 34 may be rotated on sleeve 26 in a clockwise direction in Fig. 1 to extend in the opposite direction, so that the power stick may 15 be used at either side of the picker stick and either side of the loom. The arrangement shown and described outlasts the usual lug strap many times and keeps the loom in operation far longer.

Having thus described my invention and the 20 advantages thereof, I do not wish to be limited to the details herein disclosed, otherwise than as set forth in the claims, but what I claim is:

1. In a loom, a power stick comprising an elongated element, a pair of spaced plates for connection to a sweep stick, a pivot connection between one plate and the element, so that the plates are completely reversible relative to the element, and an offset holder secured to said one strap and embracing the power stick element, 30 and a bumper spacing the plates, a fastener thru the bumper, said fastener securing the holder to said one plate.

2. In a loom, a picker stick, a stud shaft, a power stick holder on the stud shaft, a power stick 35 longitudinally adjustable in the holder, a plate, an offset element secured to the plate, a fastener extending through the offset element, the power stick, and the plate and pivoting the latter to the power stick, a second plate, the two plates containing the picker stick, a bumper between the plates, said bumper being rotatable to present a plurality of bumping faces to the picker stick, and a sweep stick secured to the plates.

3. A loom as recited in claim 2 including a 45 detachable bumper plate for the bumper, and means on the bumper plate detachably securing the same to the aforementioned plates.

4. A loom as recited in claim 2 including means on the first plate projecting into the space between the plates to insure the picker stick striking the bumper centrally thereof.

FRANK L. FURGAL.
